United States Patent Office

Des. 176,167
Patented Nov. 22, 1955

176,167

SHOE

Shirley J. White, Big Spring, Tex.

Application March 8, 1955, Serial No. 34,946

Term of patent 7 years

(Cl. D7—7)

FIG. 1

FIG. 2

FIG. 3

Fig. 1 is a view in side elevation of a shoe, showing my new design, which is the same as the opposite side;

Fig. 2 is a top plan view thereof;

Fig. 3 is a rear elevational view thereof.

The dominant features of my design reside in the portions shown in full lines.

I claim:

The ornamental design for a shoe, as shown and described.
